UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

PAPER-CRINKLING MACHINE.

Application filed September 2, 1920. Serial No. 407,686.

To all whom it may concern:

Be it known that I, WILLIAM A. LORENZ, a citizen of the United States, residing in Hartford, in the county of Hartford and 5 State of Connecticut, have invented certain new and useful Improvements in Paper-Crinkling Machines, of which the following is a specification.

This invention relates to an apparatus for 10 crêping paper, and particularly to means for advancing the paper against a doctor-blade or crinkling element.

It has been usual to run the moistened 15 paper over a rotating cylinder, excessive moisture being pressed out of the paper by means of a roll, the roll also causing the paper to stick to the surface of the cylinder. The cylinder has therefore been enabled to 20 drive the paper edgewise with considerable force against the doctor-blade whereby it has been crushed or crinkled and also stripped from the cylinder.

One of the objects of the present invention is to provide for successful crinkling 25 of the paper even though not saturated by moisture, and even though the paper is only sufficiently dampened to cause it to adhere slightly to the rotating cylinder, or not dampened at all, or in case the paper is 30 heavy and stiff and hence not well adapted to bend around and adhere to the cylinder. It will be understood that the stiffness of the paper renders it inapt to stick to the cylinder and inclines it to assume a straight 35 form, and hence to separate itself from the cylinder; while, owing to this stiffness, the resistance of the paper being crinkled, is increased. In other words, the grip of the cylinder on the paper is diminished, while the need arises for crushing the paper with greater force against the doctor-blade.

In overcoming this difficulty, there is provided an endless driving belt, preferably of 45 greater breadth than the web that is to be crinkled; and this belt is arranged to run around the cylinder from the introductory side thereof to the doctor-blade, and to confine the web tightly against the cylinder and crush it edgewise with force against the doctor-blade, thereby successfully crinkling comparatively dry paper, as well as slightly or moderately moistened heavy paper. The

advancing edge of the doctor-blade may extend into the bight between the cylinder 55 and the belt, as the latter in leaving the cylinder runs over a guide-roll; and hence the driving power of the belt may be exerted substantially up to the point where the latter begins to crinkle against the doctor-blade, whereby a forcible delivery of 60 the paper against the doctor-blade is assured.

Another feature of the invention relates 65 to forming figures or other ornamentation upon the crêped paper. This may be done at the same time as the crinkling, and may be effected by forming intaglio or recessed designs upon the belt, which may be of suitable, strong, tough material. The portions 70 of the paper which overlie the intaglio designs are not crinkled in the same manner nor to the same extent as the other portions of the paper, so that a difference in appearance of the paper is created, the outlines of these different portions corresponding 75 to the outlines of the patterns in the belt. The crinkling elements may be set so closely together as to cause a tendency of the paper at the crinkling point to be forced 80 into the depressed patterns in the belt, thereby to form a raised design upon the paper.

Other features and advantages will hereinafter appear.

In the accompanying drawings, in which the invention is illustrated diagrammatically,

Figure 1 is a plan of crinkling machinery embodying the present improvements.

Figure 2 is a sectional elevation thereof, taken at about the line 2—2, Figure 1.

Figure 3 is an elevation drawn upon a larger scale, and represents a section of the machine taken about the line 3—3, Figure 1.

Figure 4 is a sectional elevation to illustrate the mounting of the ends of the belt roll at the doctor-blade, and illustrates how this roll constantly presses the belt against 100 the paper on the cylinder. This figure also shows means for closely adjusting this belt roll relatively to the surface of the crinkling cylinder.

Figure 5 illustrates a design formed in 105 intaglio upon the belt, to produce corre-

sponding designs upon the crinkled paper.

The web may be supplied in the form of a roll 10, mounted upon a spool 11 and retarded by a weighted strap or brake 12.

5 The paper is led over an idle roll 13, and thence around a main cylinder 14; the paper being moistened or steamed upon one or both sides by means of sprinkling pipes 15, 16. The paper in passing downwardly 10 between the rolls 13, 14, comes under the control of an endless belt 17, which holds the paper to the cylinder until the paper reaches the doctor-blade 18, the latter adjustably mounted by bolts 19 upon a cross 15 bar 20, and having a smooth edge to engage the smooth surface of the main cylinder, and an angular front face. From the cylinder the endless belt returns over rolls 22, 23, 24. The belt may be tightened by 20 swinging the roll 22 to the left at Figure 2, this roll being mounted upon a pair of arms 25, journaled upon a fixed shaft 26 and having a split hub and bolts 27 for fastening the arms where adjusted, to secured and 25 maintain the tautness of the belt.

The main crinkling cylinder 14 may be driven by a pulley 28, having a pinion 29 to mesh with a cylinder gear 30; and the roll 21, which may be utilized to perform 30 an important function in the crinkling operation, may be power-driven by means of a pinion 31, fixed upon roll shaft 32 and meshing with the main gear 30.

35 As the web of paper runs off from the spool 11 and over the roll 13, it may be moistened by water or steam on one or both sides, and from the roll 13 passes down between the belt 17 and the main cylinder or other carrier 14. The belt drives the paper 40 around the cylinder to and against the doctor-blade 18, and crinkles the paper as indicated at 33; the crinkled paper being delivered from the machine by a belt mechanism 34.

45 The roll 21 may be placed so near the doctor-blade 18 that the control of the paper by the driving belt may be maintained up to the point where the paper actually begins to crush against the blade, especially 50 if the latter be so inclined as to enter the bight or space between the roll 21 and the cylinder 14, shown at Figure 3. By means of the adjustment seen in Figure 4, the roll 21 may be set as closely as desired to the cylinder 14, so as to insure the desired 55 control of the advancing paper. The roll shaft 32 extends through a bearing or box 35 at each end of the shaft, said bearing being supported upon a screw 36, to permit fine 60 up-and-down adjustment of the shaft, thereby to regulate the closeness of the roll 21 to the main cylinder 14; and compression spring 37 may be adjusted by screw 38 against the block 35, to hold the latter firmly 65 down upon the screw 36 at each end of the

roll; the screw 38 being secured by a nut 39. Thus exactly the right relation may be secured between the roll and the main cylinder, and the machine is readily adaptable to different kinds and thicknesses of paper. The paper may be driven along by reason solely of the tautness of the belt holding it against the cylinder 14, or partly by reason of the tautness of the belt and partly by reason of the pressure of the 70 springs 37, which may hold the roll down with force against the belt and paper; this result being secured by adjustment of the screws 36. The doctor-blade may be placed at different angles, and may be inserted 75 more or less into the bight between the rolls 21 and 14, according to the requirements of the work to be done. The tautness of the belt alone may be relied upon in some cases 80 to carry the paper against the doctor-blade, and the latter may be set as close as desired 85 to roll 21 and the belt thereon.

If desired, the belt may be formed with intaglio designs or depressions 40, Figure 5, upon the face thereof next to the paper, so 90 that corresponding designs will appear in the crinkled paper delivered from the machine. Owing to such portions of the belt being cut away, there will be a tendency of 95 the crinkling paper to force its way into the depressions, thereby producing raised designs upon the crinkled sheet; and the crinkling or condition of the paper within 100 said designs will be different from that of the body-portion of the paper, so that the 105 designs will become prominent and attractive. For forcing the crinkling paper into the designs, the blade 18 may be set more closely towards the roll 21 than shown in the drawings, if desired. The belt may be 110 made of leather, rubber, metal or any preferred material.

The roll 24 may also be provided with 115 adjustable springs 37 and set screws 36 and bearings 35, if desired.

Variations may be resorted to within the scope of the invention, and portions of the improvements may be used without others.

Having thus described my invention, I 115 claim:

1. A paper-crinkling machine comprising, in combination, a main cylinder or carrier, a doctor-blade therefor, an endless belt to run partly around the cylinder to the doctor-blade, and means for leading the paper to the belt and cylinder to be driven thereby against the doctor-blade, intaglio designs being formed upon said belt, for producing corresponding designs or effects in the crimped web. 120

2. The combination with a doctor-blade or crinkling element, of means to co-operate therewith for producing a compound design upon paper, including means to advance the paper to the doctor-blade or 125 130

crinkling element, and means provided upon said advancing means, for controlling an element of the compound design.

3. The combination of a cylinder or carrier, a belt for carrying the paper on the cylinder, means for advancing the paper with the cylinder and belt, a doctor-blade against which the paper is crinkled, and

guide-rolls for guiding the belt on the cylinder and off the cylinder, the belt being provided with recesses in designs for forming designs or effects on the crinkled fabric. 10
